CLAIM

The ornamental design for an surgical eye restraint instrument, as shown and described.

DESCRIPTION

FIG. 1 is a perspective view of the surgical eye restraint instrument of the present invention showing my new design; FIG. 2 is an enlarged partial perspective view of the head portion of the surgical eye restraint instrument thereof; FIG. 3 is a front elevational view thereof, the rear elevational view being identical thereto; and, FIG. 4 is a side elevational view thereof, the opposite side elevational view being identical thereto.
